UNITED STATES PATENT OFFICE.

GEORGE S. KNAPP, OF LA GRANGE, ILLINOIS, ASSIGNOR TO KNAPP BROTHERS MANUFACTURING COMPANY, OF CHICAGO, ILLINOIS, A CORPORATION OF ILLINOIS.

CHALK-TROUGH FOR BLACKBOARDS.

1,279,554.

Specification of Letters Patent. Patented Sept. 24, 1918.

Application filed July 20, 1918. Serial No. 245,820.

To all whom it may concern:

Be it known that I, GEORGE S. KNAPP, a citizen of the United States, residing at La Grange, in the county of Cook and State 5 of Illinois, have invented certain new and useful Improvements in Chalk-Troughs for Blackboards, of which the following is a specification.

This invention relates to improvements 10 in chalk troughs, particularly for use in connection with blackboards and the like, and the object of the invention is to provide a simply constructed and readily installed device of this character and one which is 15 neat and attractive in appearance, sanitary in construction and having a removable false bottom in the trough for normally holding the crayon and erasers and to receive the crayon and other dust and which 20 false bottom may be readily removed for cleaning and other purposes.

Other objects of this invention include improvements in details of construction and arrangement whereby a very simple and 25 attractive construction of this type is provided.

To the accomplishment of the foregoing and such other objects as may hereinafter appear my invention consists in the construction, combination and arrangement of 30 parts hereinafter described and then sought to be defined in the appended claims, reference being had to the accompanying drawings forming a part hereof and which 35 shows, merely for the purpose of illustrative disclosure, a preferred embodiment of my invention, it being expressly understood however that various changes may be made in practice within the scope of the claims 40 without digressing from my inventive idea.

In the drawings,

Figure 1 represents a perspective view 45 of a device constructed according to my invention installed in position for use.

Fig. 2 is a vertical transverse cross section through the same taken substantially on line 2—2 of Fig. 3.

Fig. 3 is a top plan view of one end of the same, part of the false bottom being removed to show details of construction.

Referring now to the drawings, the numeral 1 designates the blackboard or other surface to which the device is adapted to be attached. The device itself comprises the 55 body part 2, which is preferably formed of

an elongated integral piece of sheet metal bent or shaped to provide a trough part which includes an outwardly curved or convex rear wall 3, a flat bottom part 4, an outwardly inclined front wall 5, bent over, as 60 at 6, and then downwardly, as at 7, to form the outer front wall having the downwardly inclined portion 8 terminating in the substantially straight edge part 9, the parts 8 and 9 forming a support for the trough provided by the parts 3, 4 and 5, and the edge bearing against the wall or surface, as indicated.

The ends of this elongated member 2 are closed by the end pieces 10 which are shaped, 70 as shown, and are formed with the flange 11 corresponding substantially in shape to the cross section of the member 2, the ends of which rest against the said flange, as clearly shown in Fig. 2. Each member 10 is also 75 provided with the projection 12 to receive the securing means 13 by which the member 2 is connected thereto.

Removably mounted in the trough provided in the top part of member 2 is the 80 false bottom member 14, which is crimped, as shown, to provide a plurality of corrugations or ridges 15 and having its edges resting against the front and rear parts 3 and 5 of the member 2, as shown. This 85 member 14 is frictionally held in position and is readily removable therefrom for cleaning and other purposes and when in position receives the dust and chalk from the black board, the crayon, the erasers and other articles, it being noted that the concave shape of the rear wall 3 will prevent any of the crayon dust and dirt from dropping into the trough underneath the false 90 bottom member 14.

Having described my invention, what I 95 claim is:—

1. A chalk trough of the character described including an elongated body member formed of sheet metal to provide a trough part and a bracing part therefor, and a false bottom member transversely crimped to provide a plurality of longitudinally extending ribs and alternate depressions removably mounted in said trough 100 part.

2. A chalk trough of the character described including an elongated body member formed of sheet metal to provide a trough part and a bracing part therefor, 110

and a false bottom member removably mounted in said trough part, said false bottom member being crimped to provide a plurality of corrugations.

- 5 3. A chalk trough of the character described including in combination an elongated body member formed of an integral piece of sheet metal and shaped to provide a trough part having a convexed rear wall 10 and an outwardly inclined front wall and also having a brace part extending thereunder to a point in the same vertical plane with the rear wall of the trough part, end members for said body member, each having 15 a flange shaped to correspond to the cross sectional shape of the body member to receive the end edges thereof, and a removable false bottom positioned in said trough part.
- 20 4. A chalk trough of the character de-

scribed including in combination an elongated body member formed of an integral piece of sheet metal and shaped to provide a trough part having a convexed rear wall and an outwardly inclined front wall and 25 also having a brace part extending thereunder to a point in the same vertical plane with the rear wall of the trough part, end members for said body member, each having a flange shaped to correspond to the cross 30 sectional shape of the body member to receive the end edges thereof, and a removable false bottom positioned in said trough part, said removable false bottom being crimped to provide a plurality of corruga- 35 tions.

In testimony whereof I hereunto subscribe my name.

GEORGE S. KNAPP.
